UNITED STATES PATENT OFFICE

HARRY JOHN WILLIAMS, OF ZEPHYRHILLS, FLORIDA

DESIGN FOR A FIGURE TOY

Application filed October 19, 1932. Serial No. 45,418. Term of patent 3½ years.

To all whom it may concern:

Be it known that I, HARRY J. WILLIAMS, a citizen of the United States, residing at Zephyrhills, in the county of Pasco and State of Florida, have invented a new, original, and ornamental Design for Figure Toy, of which the following is a specification, reference being had to the accompanying drawing, forming part thereof.

I claim:

The ornamental design for a figure toy as shown.

HARRY JOHN WILLIAMS.
